UNITED STATES PATENT OFFICE.

JOHN J. TIERNEY, OF SLEEPY EYE, MINNESOTA, ASSIGNOR OF ONE-THIRD TO DESMOND P. TIERNEY, OF SLEEPY EYE, MINNESOTA.

TIE-TAMPING MACHINE.

Application filed December 2, 1922. Serial No. 604,515.

To all whom it may concern:

Be it known that I, JOHN J. TIERNEY, a citizen of the United States, resident of Sleepy Eye, county of Brown, and State of Minnesota, have invented certain new and useful Improvements in Tie-Tamping Machines, of which the following is a specification.

This invention relates more particularly to machines designed for use in tamping or packing ballast under the ties of a railroad track.

In railroad construction, the ties to which the rails are spiked are embedded in ballast such as crushed rock, gravel or other suitable material, which is packed firmly under and against the ties to hold them securely in the proper position so that each tie will carry its portion of the load and provide a uniform support for the rails throughout their entire length. Owing to the severe use to which a railroad track is subjected unusual care is required in tamping or packing the ballast material under the ties so that they will be uniformly and firmly packed to prevent them from becoming loosened and thus ineffective, due to the weight and vibration of heavily laden trains moving rapidly thereover. It is also frequently necessary to repack the ballast around the ties of an old track for the purpose of straightening and leveling the track. Heretofore, it has been customary to tamp the ballast by hand tampers or by the use of mechanical devices either carried by the operator or mounted on heavy trucks, but this method has not proven very satisfactory as some ties have been found to be packed more firmly than others, thereby causing the rails to settle in places and thus causing the track to become rough and unsafe for use.

The novel tamping machine shown in this invention is mounted upon a wheeled frame of light weight, and is particularly adapted to be used by section crews in repairing and maintaining tracks that are in service, such as repacking the ballast under ties that have become loosened and also to tamp the ballast under new ties that are substituted for those deteriorated or worn. It may be operated either by hand or power as desired. When power-driven, the power is preferably transmitted by a flexible belt from the usual railway motor car connected to the tamping machine by the usual draw-bar connection.

Due to its light weight the machine may be readily and quickly removed from the tracks by the section crew to clear the tracks for an approaching train. The tamping blades are also adjustable to suit all conditions and thus assure uniform and thorough tamping.

The object of this invention therefore is to provide an improved tie-tamping machine.

Other objects of the invention will more fully appear from the following detailed description and the accompanying drawings and will be pointed out in the annexed claims.

In the accompanying drawing there has been disclosed a structure designed to carry out the objects of the invention, but it is to be understood that the invention is not confined to the exact features shown, as various changes may be made within the scope of the claims which follow.

In the drawings:

Figure 1 is a sectional view in side elevation, showing the tamping blades lowered and in position to tamp the ballast under the tie.

Figure 2 is a similar view, but showing the tamping blades and frame raised to clear the ties for traveling on the railroad.

Figure 3 is a vertical sectional view on the line 3—3 of Figure 2, showing the tamping blades in a raised position.

In the selected embodiment of the invention here shown, there is illustrated a tie-tamping machine mounted upon supporting means, such as a wheeled frame or truck comprising a frame 6, axles 7 and the usual carrying wheels 8, adapted to rest and travel upon the usual rails 5 of a railroad track. Couplings 9, of usual construction, are preferably provided at each end of the frame 6, to afford means whereby the tamping machine may be coupled to a railway motor car, well known to the art, for the purpose of moving the machine along the railroad track. A platform 10 is preferably provided at one end of the machine for an operator to stand on to adjust the tamping blades while the machine is in operation.

A plurality of suitable supporting frames 11, carrying the tamping tools and operating mechanism, are adjustably mounted upon the truck frame 6, preferably by means of suitable bell-crank 12 and lift links 13. These bell cranks, preferably four in num-

ber, are rigidly secured to the terminal ends of a pair of shafts 14, rotatably mounted in the side beams of the frame 6, one of said shafts being adapted to pass through and engage elongated openings or slots 15, provided in the vertical side members of the frames 11. A similar shaft 14 is rigidly mounted in the frame 6 and in like manner adapted to engage similar slots 15 in the other vertical side members of the frames 11. The function of the slots 15 is to guide the frames 11 in their up and down movement and also to limit their movement. Each one of the four lift links 13 has its upper end pivotally connected to one arm of one of the four bell cranks 12, the lower ends of these links being pivotally connected respectively to one of the four ends of a pair of shafts 16, which are mounted to oscillate in suitable bearings 17 provided in the lower downwardly extending arms 18 which are preferably integral with the lower portions of the frames 11. The corresponding arms of the bell cranks 12, on each side of the truck frame, are pivotally connected together by suitable connecting rods 19, shown in Figures 1 and 2. A hand lever 20 is rigidly mounted upon the shaft 14, adjacent the platform 10 and has a latch 21 of usual construction adapted to engage a notched quadrant 22 secured to one of the side beams of the truck frame 6. The function of this lever is to raise and lower the supporting frames 11 by means of the bell-cranks 12 and lift links 13, hereinbefore described.

A plurality of tamping bars 23, having suitable tamping blades or tools 24 rigidly secured thereto, are slidably mounted to reciprocate in suitable bearings 25 provided in brackets or yokes 26 fixedly mounted upon the oscillatory shafts 16, as shown in Figure 1. Pivot blocks 27 are secured to the tamping bars 23, preferably between the bearings 25 of the yokes 26, and have pivot pins 28 rigidly mounted therein and adapted to be respectively engaged by elongated apertures 29 provided in forked arms 31, each loosely mounted upon a portion of one of a pair of shafts 32 secured to the supporting frames 11. Arms 33 which are preferably integral with the forked arms 31 and project inwardly therefrom, have their ends pivotally connected by pins 34 to the lower ends of suitable connecting rods 35. The upper ends of the connecting rods are provided with capped bearings 36 mounted upon suitable eccentrics 37 secured to a drive shaft 38 rotatably mounted in capped bearings 39 in the supporting frames 11. It is preferred to employ square bar iron in the construction of the tamping bars to prevent the bars from turning axially in the bearings 25 which bearings are correspondingly squared to receive the bars, thereby always keeping the bottom or tamping edge

of each blade 24 on substantially a horizontal line.

Thus, upon rotation of the drive shaft 38 the connecting rods 35 will be reciprocated and the arms 33 and 31 will similarly actuate the pivot blocks 27 and thereby cause the tamping bars 23 to move up and down in rapid succession and thus firmly pack the ballast under the ties.

Means are also provided whereby the tamping bars and blades may be readily and quickly adjusted to conform to the width of each tie. A hand lever 40 having a latch 41 (see Figure 2) is pivotally mounted upon a pin 42 rigidly mounted in a bracket 43 which is secured to one of the supporting frames 11 by any suitable means such as bolts 44. A notched quadrant 45 is supported by the bracket 43 and is adapted to be engaged by the latch 41 of the lever 40. An arm 46, preferably integral with the lower end of the hand lever 40, is pivotally connected to one end of a connecting rod 47. The other end of the connecting rod is similarly connected to an arm 48 rigidly mounted upon the shaft 16 beneath the hand lever. A similar arm 49, preferably integral with the arm 48, is pivotally connected to one end of a connecting rod 51 while the other end of this connecting rod is connected to a depending arm 52 secured to the other shaft 16. Movement of the hand lever 40 may therefore simultaneously oscillate the two shafts 16 in opposite directions in their bearings 17. The tamping bar-supporting yokes 26, being rigidly mounted upon these shafts, will correspondingly oscillate the tamping bars and blades, as shown by dotted lines in Figure 2. A drive pulley 53, rigidly mounted upon the drive shaft 38, and a flexible belt 54 are provided for the transmission of power to the tamping machine from the usual railway motor car, coupled to the tamping machine by the usual draw bar connection.

The tamping bars and blades of this novel tamping machine are preferably arranged, as shown in Figure 3, so that the end blades will tamp and pack the ballast adjacent each side of the rail, while the center blades will tamp the ballast under the ties at the center of the railroad track. Also the angular relations of the eccentrics 37, for the connecting rods 35, are preferably arranged upon the drive shaft 38 in such a manner as to vary the timed relation of the downward working travel of the tools, such, for example, as to cause the tamping blades to operate progressively along both sides of the tie.

The tamping blades may be adjusted to and from the tie by an operator standing on the platform by means of the hand lever 40. They may also be elevated or depressed by means of the hand lever 20 while the ma-

chine is in operation, thus permitting the required adjustments to enable the device to be universally used for packing ballast under the ties of any railroad.

5 Having thus described my invention, what I claim as new and desire to secure by Letters Patent, is:

1. A tie-tamping machine including a supporting means, a plurality of tamping tools 10 mounted to reciprocate on the supporting means and adapted to tamp adjacent the sides of ties, a member rotatably borne by said supporting means, eccentric means on said rotatable member, and driving connection 15 between said tools and said eccentric means whereby, upon rotation of said member, the tools are reciprocated.

2. A tie-tamping machine including a supporting means, a plurality of tamping tools 20 mounted on the supporting means to reciprocate in opposed pairs and adapted to tamp opposite sides of ties, a drive-shaft rotatably borne by said supporting means, eccentrics on said drive-shaft, a driving connection between each tool and an eccentric whereby, upon rotation of the drive shaft, the tools are reciprocated.

3. A tie-tamping machine including a supporting means, a plurality of tamping tools 30 mounted on the supporting means to reciprocate in opposed pairs and adapted to tamp opposite sides of ties, a member rotatably borne by said supporting means, eccentric means on said rotatable member, and driving connection between said tools and said eccentric means whereby, upon rotation of

said member, the tools are reciprocated, said eccentric means being arranged to vary the timed relation of the working travel of the tools.

40

4. A tie-tamping machine including a supporting means, a plurality of bearings pivotally mounted upon the supporting means in opposed pairs, a tamping tool reciprocably mounted in each bearing and adapted to 45 tamp on one side of a tie, a rotatable member mounted upon the supporting means, eccentric means on said member, a driving connection between each tool and said eccentric means whereby, upon member rotation, 50 each tool is reciprocated, and means to alter said pivoted bearings to change the tamping position of each tool.

5. A tie-tamping machine including a supporting means, a plurality of bearings pivotally mounted upon the supporting means, in opposed pairs, a tamping tool reciprocably mounted in each bearing and adapted to 55 tamp on one side of a tie, a rotatable member mounted upon the supporting means, eccentric means on said member, a driving connection between each tool and said eccentric means whereby, upon member rotation, 60 each tool is reciprocated, means to alter said pivotal bearings to change the tamping position of each tool, and means connecting together opposed pairs of bearings for simultaneous pivotal movement whereby the bearing of each pair is simultaneously altered.

In witness whereof, I have hereunto set my 65 hand this 24th day of November 1922.

JOHN J. TIERNEY.
